UNITED STATES PATENT OFFICE.

LAWRENCE G. MCKAM, OF DETROIT, MICHIGAN.

RAILWAY-CROSSING.

1,372,889.

Specification of Letters Patent. Patented Mar. 29, 1921.

Application filed March 11, 1920. Serial No. 364,884.

To all whom it may concern:

Be it known that I, LAWRENCE G. MCKAM, a citizen of the United States of America, residing at Detroit, in the county of Wayne 5 and State of Michigan, have invented certain new and useful Improvements in Railway-Crossings, of which the following is a specification, reference being had therein to the accompanying drawings

10 The invention relates to railway crossings of that type in which the intersecting portions of the rails are integral and are transversely grooved for the passage of the wheel flange. It is one of the objects of the invention to obtain a construction in which 15 pounding of the wheels when crossing the grooves is prevented. Another feature of the invention is the means employed for joining the integral crossing portions with 20 the rail sections, and the invention further comprises various specific features as hereinafter set forth.

In the drawings:

25 Figure 1 is a plan view of the crossing; Fig. 2 is a perspective view of one of the crossing members;

Fig. 3 is a longitudinal section on line 3—3 of Fig. 1;

30 Fig. 4 is a horizontal section showing the manner of joining the rail sections to the crossing section.

A and A' are the rails of one track, and B and B' are the rails of the intersecting track. C are rail chairs located at the points 35 of intersection of the rails of the crossing tracks. These chairs are preferably formed of integral castings having transversely extending rail sections D and D' with connecting fillets E and transversely extending

40 grooves F and F' for the passage of the wheel flanges. The grooves F and F' are of such a depth as to engage the periphery of the wheel flange so as to take the load on the wheel while crossing the intersecting groove.

45 With certain constructions that have heretofore been employed the bottoms of the grooves of the chair have been curved upward to the point of intersection with the transverse groove, so that the wheels in

50 crossing the joint are lifted to clear the tread portion from the top surface of the rail. This has the objection of forming a bump over which each wheel must pass, interfering with the smoothness of travel 55 and requiring the overcoming of the inertia of the load in changing the direction of

movement thereof. With my improved construction this defect is avoided by forming the bottoms of the grooves F and F' substantially straight and of a depth to engage 60 the wheel flanges without either raising or lowering the wheels. Inasmuch, however, as the passing of the tread portion of the wheel over the transverse groove will cause a pounding where any load is carried 65 through the tread, I have depressed the portions of the rail on opposite sides of each groove. Thus, as shown in Fig. 3, the portions G are gradually inclined or curved downward toward the groove, so that when 70 a wheel, such as H, is crossing the groove the entire load is carried upon the flange I. This will avoid any pounding and the gradual incline of the rail will permit of 75 picking up the load upon the tread without any pounding.

The chairs C are connected to each other by rail sections J. These are secured in position by fish plates K and the construction is preferably such that the fish plates extend 80 the entire length of the rail sections and overlap sections of the chair. These fish plates are then bolted through the web of the rail and the web of the chair, as indicated at L, and are secured to the track sections A 85 and B in a similar manner.

The construction as described can be cheaply manufactured and more easily installed than constructions where the entire crossing is formed integral.

90 What I claim as my invention is:

1. A railway crossing, comprising chairs forming the intersections of the crossing rails, each of said chairs having transverse grooves therein for receiving the wheel 95 flange, the bottoms of said grooves being substantially straight and of a depth to contact with the periphery of the wheel flange when the tread of the wheel is resting upon the top of the normal tread surface, and the portions of the top of the normal tread surface on opposite sides of said grooves being tapered to relieve contact with the tread while traversing the groove, sections of standard rail interposed between companion arms of 100 the chairs to form substantially unbroken continuation of the arms and fish plate connections between the arms and the interposed rail sections.

2. A railway crossing, comprising chairs 110 forming the intersections of the crossing rails, each chair being provided with trans-

versely extending grooves therein for the reception of the wheel flange, the bottoms of said grooves being straight and of a depth to be tangent to the wheel flange when the 5 tread of said wheel is resting upon the top of the rail, and the end portions of the top of the rail on opposite sides of said grooves being gradually tapered to transfer the load to the flange while passing the groove, the 10 chairs having outwardly extending arms adapted to form substantially continuous and unbroken connections with the surfaces of standard rails, rail sections inter-connecting the inner arms of the chairs and forming 15 tread surfaces with the arms thereof which are substantially unbroken and fish plates secured to the webs of the rail sections and the corresponding webs of the arms of the chairs.

20 3. A railway crossing, comprising a chair for each rail intersection formed of an in-

tegral block having transverse grooves there-
in for receiving the wheel flange and rail
treads conforming to standard rail tread
proportions, the bottoms of said grooves be-
ing substantially unbroken and with a depth
to contact with the periphery of the wheel
flange when the tread of the wheel is resting
at the top of the normal tread portion and
the portion of the top of said chair on oppo-
site sides of said grooves being depressed to
relieve contact with the tread while the wheel
is traversing the grooves, rail sections inter-
posed between and abutting against cor-
responding arms of the chairs, the rail sec-
tions forming substantially unbroken and
continuous extensions of the arms, and fish
plate connections bolted to the webs of the
interposed rail sections and the correspond-
ing webs of the chair extensions.

In testimony whereof I affix my signature.

LAWRENCE G. MCKAM.
